(57) **CLAIM**

The ornamental design for a hat with back opening as shown and described.

DESCRIPTION

FIG. 1 is a rear perspective view of a hat with back opening showing a first embodiment of our new design;

FIG. 2 is a front view thereof;

FIG. 3 is a rear view thereof;

FIG. 4 is a right side view thereof;

FIG. 5 is a left side view thereof;

FIG. 6 is a top view thereof; and

FIG. 7 is a bottom view thereof.

FIG. 8 is a rear perspective view of a hat with back opening showing a second embodiment of our new design;

FIG. 9 is a front view thereof;

FIG. 10 is a rear view thereof;

FIG. 11 is a right side view thereof;

FIG. 12 is a left side view thereof;

FIG. 13 is a top view thereof; and,

FIG. 14 is a bottom view thereof.

The long dash-short dash broken lines in FIGS. 1-7 showing a snap depict portions of the hat with back opening that form no part of the claimed design. The remainder of the long dash-short dash broken lines indicate the bounds of the claimed design and otherwise form no part of the claimed design. The even-length broken lines, including apparent stitching lines, depict portions of the hat with back opening that form no part of the claimed design.
